OR

D 13,408

EX

No. 13,408

Nov 14, 1882

UNITED STATES PATENT OFFICE.

JOHN L. POPE, OF CLEVELAND, OHIO.

DESIGN FOR A WEAR-IRON.

SPECIFICATION forming part of Design No. 13,408, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and 5 original Design for Wear-Irons, of which the following is a specification, reference being had to the accompanying engraving, forming part thereof.

I have invented a design for wear-irons 10 adapted for use on carriages and other vehicles, which consists in ornamenting the outer or upper surface thereof with a bead or molding that is flat on top and beveled on the sides, substantially as shown and hereinafter more 15 particularly described.

It will be seen in the accompanying drawing that the wear-iron is provided with three elongated lugs having perforations, at which 20 points the iron is attached by suitable devices to the desired part of the vehicle.

On the upper or exposed face of the article I have produced my new design, where will be found a sort of molding or bead, A, that has a flat top, as at *a*, and beveled sides or edges, as at *b*. This flat portion *a* may be slightly 25 depressed or elevated, to suit the tastes of the manufacturer and user, and either construction I would consider to be within the bounds of my invention.

What I claim as my invention, and desire to 30 secure by Design Letters Patent, is—

A wear-iron having its upper surface ornamented with flat and beveled portions, substantially as shown and described.

In testimony whereof I have hereunto set my 35 hand this 22d day of June, 1882.

JOHN L. POPE.

In presence of—

CHAS. W. MOSES,
C. M. COPP.
